ELECTRICAL CONNECTOR

Arthur J. Schmitt, Chicago, Ill.

Application December 5, 1940, Serial No. 368,658

4 Claims. (CL 173—328)

This invention relates to electrical connectors more particularly of the so-called automatic safety grounding class in which the separation of electrodes causes certain of them to be electrically grounded and, conversely, interengagement of electrodes breaks the grounding contact.

A useful application of such a connector is on aircraft for automatically grounding the magneto to the engine frame when the device is disconnected, thus eliminating the danger of injury to personnel which might otherwise be caused by accidental starting of an engine should the propeller be moved during inspection or while minor repairs are being made.

The present invention aims to provide an improved connector of this class more particularly for a three wire system which can be produced in large quantities at relatively low cost by reason of simplicity of construction and ease of assembly, and which at the same time is sturdy and unfailing in operation, so as to be especially adapted for use where maximum safety is imperative.

A further object of the invention is to provide an insulating connector core for a connector of this class which is readily removable from its shell and which may be assembled with either a receptacle type shell or a plug type shell, interchangeably, thus enhancing the adaptability and versatility of the connector.

Other objects and advantages will be apparent from the following description, taken together with the accompanying drawing, in which—

Figure 1 is an exploded view showing shell parts with which my improved connector may be associated;

Figure 2 is an enlarged sectional view of one form of assembly of my improved connector with the shell parts shown in Fig. 1;

Figure 3 is a cross-section taken on the line 3—3 of Fig. 2;

Figure 4 is a side elevational view, on the scale of Fig. 1, of a preferred form of insulating core for my improved connector;

Figure 5 is a dissociated somewhat diagrammatic view of the connector core contact members and associated prongs of the circuit continuing element, with exemplary wiring therefor; and

Figure 6 is a sectional exploded view showing an alternative form of assembly.

Referring in detail to the illustrative embodiment of my invention shown in the drawing, and turning first to Fig. 4, I have shown an insulating

cylindrical core 10 composed advantageously of a molded phenolic condensation product, the core having a cylindrical enlargement 11 at one end and being axially recessed as at 12 (Fig. 3), to house the contact members 13, 14 and 15 shown in Fig. 5, as presently described more in detail. A similar insulating disk 16 completes the core 10, mating with the core enlargement 11, perforated as at 17 in three separate apertures to permit it to pass over and be retained on the core by the snug fit in said apertures 17 (Fig. 2) of the integral tails 13a, 14a and 15a of the contacts 13, 14 and 15. As later described, the disk 16 also holds the contacts in place.

The contact members 13, 14 and 15 are desirably of phosphor bronze, silver plated for enhanced conductivity, and are here shown of square cross-section so that their end terminations are received snugly in square counter recesses 18 in the opposite end of the core, which is closed by the integral wall 19 except where perforated as at 20 in three separate apertures aligned with the apertures 17. Thus the contact members are held against rotation in the core. The contact members 13, 14 and 15 are adapted to interengage with electrode-like members and in this instance are centrally axially bored as at 21 to receive the prongs 22, 23 and 24, the prongs passing through the apertures 20 when appropriately positioned in a manner and by means presently further described.

As best shown in Fig. 5, in accordance with the present invention, one of the contacts, in this instance the contact 13, has riveted thereto as at 25, a metallic grounding clip 26 fixed transversely of the contact member and having its free ends bowed as at 27. The clip also clamps to the contact member 13 the fork 28 having a pair of spring fingers 29 lying along and on each side of the contact 13 but angled away from this contact 13 each toward one of the contacts 14 and 15 so as to be resiliently pressed against these latter contacts and under certain conditions to make an electrical engagement therewith. In order to break this electrical engagement when the prongs 23 and 24 are inserted in the contacts 14 and 15 respectively, these latter parts are arcuately notched as at 30 respectively, in the vicinity of their engagement point with the spring fingers, to have laid across them in the notches 30 the semi-cylindrical cam bar 31 of an insulating phenolic condensation product. The rounded part of the cam bar lies in the notches and when the prongs 23 and 24 are withdrawn is completely received in the notches so that at such time the

extremities 32 of the fingers 29 are permitted to engage the contacts 14 and 15, the finger extremity being flattened for this purpose to be parallel with the contact across the notch, as shown in broken lines in Fig. 2. When, however, the prongs 23 and 24 are inserted in the contacts 14 and 15, since the notches 30 intersect the bores 21 of the contacts, the prongs ride over the rounded face of the cam bar, their ends being tapered as is well known, and cam the bar outwardly of the notches 30. The cam bar thus is pressed against the flattened extremities 32 of the spring fingers 29 and moves these fingers out of engagement with the contacts 14 and 15, as shown in full lines in Fig. 2. It will be understood that it is contemplated that when the prongs 23 and 24 are received in the contacts 14 and 15 respectively, the prong 22 may be also received in the contact 13, this latter contact being desirably split longitudinally as at 33 to enhance its resilience and improve the electrical engagement between the contact 13 and the prong 22.

Having described the internal construction of the core 10, the core is assembled, for example with the plug type shell 34, by insertion of the reduced end of the core into the shell from the direction of the slightly enlarged end 35 of the shell until the exterior peripheral shoulder 36 on the core abuts the internal annular shoulder 37 in the shell, at which time the enlarged portion 31 and disk 16 of the core are received in the enlarged part 35 of the shell and the closed end 20 of the core is substantially flush with the open end 38 of the shell. To prevent relative rotation between the core and the shell, the parts 35 may have rotatively interengaging shoulders. As here shown, the enlarged end 35 of the shell has an internal longitudinal feather 39 and the enlarged part 31 of the core and the disk 16 are jointly grooved as at 40 to receive the feather 39. At this time the free ends 27 of the grounding clip 26 lie in the cut-outs 41 in the core and press resiliently against the interior surface of the shell as at 42 making an electrical grounding engagement therewith. The core is desirably held in the shell by means of a spring split ring 43 which snaps into an annular groove 43a in the end 44 of the shell after the core is in place, the core disk 16 abutting the squared ends of the contacts.

In the form of assembly shown in Fig. 2, the cylindrical insulating body 45 which carries the prongs 22, 23 and 24 is assembled with the receptacle type shell 46, these parts also being splined as at 47 to prevent relative rotation, and the body 45 and its auxiliary disk 49 which functions similarly to the disk 16 are similarly held in the shell 46 by one of the spring split rings 43, indentations 49 serving to permit access for a screw driver or other removing tool to pry out the split rings when desired. The shell 46 may have a mounting flange 50 which may be perforated as at 51 for passage of screws for mounting the shell on a panel.

For completing a connection, the shell 34 with its housed core 10 has passed thereover the internally threaded coupling sleeve 52 knurled as at 53 and having an internal annular shoulder 54 which bears rotatably against the peripheral annular flange 55 on the shell 34 disposed where 70 the enlarged part 35 joins the main part of the shell 34. Also this enlarged part 35 is externally threaded as at 56 to have screwed thereon the nipple 57 which in turn is externally threaded as at 58 to have a flexible metallic conduit 58a 75

clamped thereto as by means of a clamp ring 58b. When the plug type shell 34 is then inserted into the receptacle type shell 46 and the coupling sleeve 52 tightly screwed onto the screw threads 59 of the shell 46, as at 60, Fig. 2, the core 10 is moved inwardly but non-rotatively so that the prongs 22, 23 and 24 are pushed through the apertures 20 in the core and into the contacts 13, 14 and 15 respectively.

To provide for a single relative rotative engagement of the shells 34 and 46, the parts carry interengaging expedients such as the keyway 61 extending longitudinally along the outer surface of the shell 34 from its free end 38 to the annular flange 55 and a corresponding key 62 extending on the inner surface of the shell 46 from its free end 63 to its internal shoulder 64 which retains the insulating body 45 therein. This single relative rotative position of the shells 34 and 46 and the relative rotative positions of the core 10 and shell 34 and body 45 and shell 46 as determined by the splines 39 and 41, respectively, insures that the wire 65 is in electrical engagement with the wire 66, the wire 67 with the wire 68, and the wire 69 with the wire 70. Thus, definite polarity is assured. It will be understood that the wires 65, 67 and 69 may be suitably soldered to the tails 13a, 14a, and 15a of the contacts 13, 14 and 15 as at 71 respectively, and, similarly, that the wires 66, 68 and 70 may be suitably soldered to the tails 22a, 23a and 24a of the prongs 22, 23 and 24 as at 72 respectively.

A useful operation of the device is as follows:

The wire 67 may be connected with one of the magnetos, say the left-hand, and the wire 69 with the other, say the right-hand magneto. The wire 68 may be connected with the magneto switch terminal for the left-hand magneto and the wire 70 with the magneto switch terminal for the right-hand magneto. The wire 65 may be grounded, and the wire 66 may be used or not as desired, the device functioning under some conditions with or without the wire 66 and with or without the prong 22. When the connection is made as shown in Fig. 2, and the prongs 23 and 24 are received in the contacts 14 and 15, the spring fingers 29 are insulated from the contacts so as to maintain closed circuits through wires 67-68 and 69-70 respectively.

When, now, the coupling sleeve 52 is unscrewed, the shell 34 is withdrawn from the shell 46 and the circuits 67-68 and 69-70 are thus opened. Immediately upon opening of the latter circuits, the spring fingers 29, being no longer held out of contact by the prongs 23 and 24 acting through the insulating cam 31, make electrical engagement with the contacts 14 and 15 and ground these contacts and with them the magnetos through the wires 67 and 69. The grounding path is established through the spring fingers 29, the bowed clip 26, its free ends 27, the shell 34, the nipple 57, the clamp 58b and the flexible metallic conduit 58a, to the engine frame. The device will also, as will be seen, function under some conditions without the wire 65.

If it be desired to reverse the assembly, the core 10 instead of being carried by the shell 34 may be placed in the shell 46, as shown in Fig. 3, with no change necessary in the construction of the parts, but merely by removing the spring split rings 43, pulling the core 10 out of the shell 34, and inserting it into the shell 46, from which the insulating body 45 has been removed, the latter being then inserted into the shell 34, whereupon

the spring split rings 43 are replaced to hold the parts in the new assembly.

It will be understood that when the assembly of Fig. 6 is employed, the grounding path is established through the shell 46 and a metallic panel on which it may be mounted, such as a bulkhead, fire wall, or the like, or through wire 65.

Manifestly, the invention is not limited to details of construction shown for purposes of exemplification. Furthermore, it is not essential that all features of the invention be used jointly, as various combinations and sub-combinations may be advantageously employed.

Such changes may be made as fall within the scope of the following claims without departing from the invention.

Having described my invention, I claim:

1. In an electrical connector of the class described, the combination with a metallic shell, of an insulating core therein, a pair of contacts in the core having axial bores therein for receiving prong electrodes, notches in said contacts intersecting said bores, an insulating bar in said notches, said bar being rounded to be cammed by said prongs, a metallic spring clip carried by the core, cut-outs in the core permitting the free ends of the clip to engage the shell, a metallic fork connected with the clip and having a pair of spring fingers, said spring fingers being engageable with the contacts when the prongs are withdrawn and adapted to be pressed upon by said insulating bar to separate the fingers and contacts when the prongs are inserted.

2. In an electrical connector of the class described, the combination with an insulating core, of a pair of contacts having axial bores therein for receiving prong electrodes, notches in said contacts intersecting said bores, an insulating bar in said notches, said bar being rounded to be cammed by said prongs, a metallic spring clip carried by the core, cut-outs in the core through which the free ends of the spring clip project, a

metallic fork connected with the clip and having a pair of spring fingers, said spring fingers being engageable with the contacts when the prongs are withdrawn and adapted to be pressed upon by said insulating bar to separate the fingers and contacts when the prongs are inserted, whereby the contacts are alternatively in engagement either with the prongs or the fingers.

3. In an electrical connector of the class described, the combination of a pair of contact members having axial bores therein for receiving prong electrodes, notches in said members intersecting said bores, an insulating bar in said notches, said bar being rounded to be cammed by said prongs, a spring finger engageable with each contact member when the prong is withdrawn and adapted to be pressed upon by said insulating piece to separate the finger and contact member when the prong is inserted, whereby the contact is alternatively automatically in engagement either with the prong or the finger but not both simultaneously.

4. In an electrical connector of the class described, the combination with an insulating core, of a pair of separated contacts carried thereby for engagement with separable electrodes respectively, a third contact also carried by said core for engagement with an electrode, a grounding connection to said third contact, a pair of metallic spring fingers electrically connected with the third contact and bearing against the pair of first mentioned contacts respectively, and insulating cam means carried by the core between the pair of first mentioned contacts and said spring fingers and actuated by interengagement of the said first mentioned contacts and the electrodes to abut the spring fingers and move them into position insulated from the said first mentioned contacts, whereby when said electrodes are removed the said first mentioned contacts are also grounded through said grounding connection by engagement with said spring fingers.

ARTHUR J. SCHMITT.
